UNITED STATES PATENT OFFICE.

AUGUSTUS V. ALLEN, OF JOPLIN, MISSOURI.

GROOVING-MACHINE.

SPECIFICATION forming part of Letters Patent No. 376,057, dated January 10, 1888.

Application filed February 18, 1887. Serial No. 228,132. (No model.)

To all whom it may concern:

Be it known that I, AUGUSTUS V. ALLEN, a citizen of the United States, residing at Joplin, in the county of Jasper, State of Missouri, have invented a new and useful Grooving-Machine, of which the following is a specification.

My invention relates to the grooving-machine now in common use in nearly all tin-ro shops in the United States, in which the grooved wheel is carried forward and back by a crank and cogged wheel at the back end of the machine.

My object is to do away with the crank and cogged wheel and apply power to the groover direct, and also to improve the grooving-wheel. I attain these objects by the mechanism illustrated in the accompanying drawings, in which—

20 Figure 1 is a side view. Fig. 2 is a front view; Fig. 3, a side view of the grooved wheel and carriage; and Fig. 4, a front view of the grooved wheel and carriage, showing the handles attached for propelling wheel and carriage.

25 Similar letters refer to similar parts throughout the several views.

A is a stove-pipe mandrel bolted to the bench.

B is an iron arm curved at the rear end, where it is securely bolted to the mandrel.

30 C is the frame or carriage, within which runs the grooving-wheel D, the circumferen-

tial surface of which is concave to fit the convex surface of the mandrel, and provided with a groove or channel to fit the seam of the pipe. There are two smaller wheels, B, which are 35 journaled inside the carriage and bear against the lower side of the curved arm, one of which is adjustable up and down by an ordinary setscrew, (not shown,) by which means the carriage and wheels will be held rigidly in place 40 between the mandrel and arm, but will admit of free movement in and out.

The operation of the machine is as follows: The stove-pipe blank is edged and formed in the usual way, after which it is slipped on 45 the mandrel, seam up, and directly under the groove in the grooving-wheel. Now take hold of the two handles H and pull the wheel and carriage to and from you and remove the cylinder finished.

Having thus fully described my invention in its construction and operation, what I claim as new, and desire to secure by Letters Patent, is—

The combination, with a mandrel, of a curved 55 arm secured thereto, a carriage, and a grooved wheel journaled therein, the shaft of which is provided with a handle upon each end.

AUGUSTUS V. ALLEN.
